UNITED STATES PATENT OFFICE.

PETER BROTHERHOOD, OF LONDON, ENGLAND.

AIR-COMPRESSOR.

SPECIFICATION forming part of Letters Patent No. 515,282, dated February 20, 1894.

Application filed October 18, 1893. Serial No. 488,529. (No model.) Patented in England October 9, 1893, No. 18,909; in France October 9, 1893, No. 233,305, and in Italy November 4, 1893, LXVIII, 466.

To all whom it may concern:

Be it known that I, PETER BROTHERHOOD, a citizen of England, residing at Nos. 15 and 17 Belvedere Road, Lambeth, London, in the 5 county of Surrey, England, have invented certain new and useful Improvements in Air-Compressors, (for which I have obtained Letters Patent in France, dated October 9, 1893, No. 233,305; in Italy, dated November 4, 1893, 10 Vol. LXVIII, 466, and in Great Britain, dated October 9, 1893, No. 18,909,) of which the following is a specification.

My invention relates to the construction of an air compressor in which the compression 15 of the air is effected by pumps operating in three stages, these pumps being arranged in a compact and accessible form, with ample means of cooling the air during compression, as I shall describe with reference to the accompanying drawings.

Figure 1 is a vertical section on the line xx of Fig. 2 which is a plan. Fig. 3 is a part vertical section on the line yy of Fig. 4 which is a sectional plan on the line zz of Fig. 3 25 and Fig. 5 is a section of the cover on the line ww of Fig. 2.

A central cylinder A is fitted with a hollow trunk piston B. The cylinder cover has through it passages covered by an annular 30 valve C, which is held up to its seating by valves D held to their seats by springs. From the space a at the lower end of the cylinder A there are two passages fitted with valves E leading to the upper ends of two small cylinders a' a^2 which are fitted 35 with plungers b' b^2 , and from these cylinders there are passages fitted with valves F to a pipe coil G, which, as well as the cylinders A, a' and a^2 is inclosed in a water tank H.

h is the pipe which supplies water under 40 pressure to the lower part of the tank H, from the upper part of which there is a communication to a space l in the cylinder cover from which space a pipe I extends into the interior of the piston B. The pipe I is inclosed within 45 another pipe J which extends through pack-

ing up to a space j in the cylinder cover, and from this space there is an outlet passage O.

The trunk of the piston B passes through a stuffing box in the bottom of the cylinder A and is attached to a cross head N, to which 55 also are attached the plungers b' b^2 which pass through stuffing boxes into the cylinders a' a^2 respectively. The cross-head N being caused to reciprocate by a suitable motor engine, during the down stroke of the piston B 60 air is drawn in through the cover past the valve C, and air previously partly compressed into the annular space a is expelled from a past the valves E into the cylinders a' a^2 . During the up stroke of the piston B the air 65 which had been drawn into A above B is forced past the valves D in to the annular space a , and air which had been previously sent into the cylinders a' a^2 is discharged from them past the valves F into the coil G 70 whence it passes by an outlet pipe f to any suitable receptacle for the air thus highly compressed by the three stages of pumping described. While the piston B is operating on the air, it during its descent draws water 75 from the tank H by the pipe I into its interior and during its ascent it expels the water by the pipe J, circulation of water through the tank and the interior of the piston B being thus maintained, keeping the metal and 80 the compressed air comparatively cool. The cylinder cover is provided with a relief valve M.

Instead of only two cylinders a' a^2 there may be a greater number of these arranged around A and having their plungers attached 85 to the crosshead N, which in that case would have a corresponding number of arms or might be in the form of a disk.

Instead of passing the plungers b' b^2 through stuffing boxes, they may be packed as shown 90 in Fig. 5. A packing P internally coned is expanded by a cone within it which is subject to the pressure in the cylinder space above the plunger.

Having thus described the nature of my invention and the best means I know for carrying the same into practical effect, I claim—

In an air compressor, the combination of the cylinder A having an annularly valved cover, the trunk piston B connected to a re- 100

ciprocating crosshead N and having through it valved passages into the annular space α around the trunk, several smaller cylinders α' α^2 having plungers attached to the crosshead N and valved passages, from the space α to them and valved passages from them to a pipe coil G, the water tank H and the concentric pipes I and J substantially as and for the purposes set forth.

10 In testimony whereof I have signed my name to this specification, in the presence of

two subscribing witnesses, this 29th day of September, A. D. 1893.

PETER BROTHERHOOD.
